UNITED STATES PATENT OFFICE.

ROBERT ANDREW EDGAR, OF CARLYLE, KANSAS, ASSIGNOR OF ONE-FOURTH TO
HENRY T. RENTFROE AND ONE-EIGHTH TO JOHN A. SELLERS, BOTH OF CAR-
LYLE, KANSAS.

CAR-DOOR.

1,345,755.

Specification of Letters Patent.

Patented July 6, 1920.

Application filed December 7, 1918. Serial No. 265,726.

To all whom it may concern:

Be it known that I, ROBERT ANDREW EDGAR, a citizen of the United States, and a resident of Carlyle, in the county of Allen 5 and State of Kansas, have invented certain new and useful Improvements in Car-Doors, of which the following is a specification.

My invention is an improvement in car doors, and has for its object to provide a 10 door of the character specified especially designed for cars used in hauling local merchandise, or for cars where it is desired to inspect the contents at any time, and which may be applied to existing doors without 15 change in the car.

In the drawings:

Figure 1 is a perspective view of the improved car door;

Fig. 2 is a side view showing the main 20 door closed and the auxiliary door closed;

Figs. 3 and 4 are sections on the lines 3—3 and 4—4, respectively, of Fig. 2;

Fig. 5 is a partial perspective view of the 25 mounting of the auxiliary door;

Fig. 6 is a perspective view showing a portion of the mounting of the large door;

Fig. 7 is a perspective view of one of the 30 latches.

The present embodiment of the invention 35 is shown in connection with a freight car 1 of usual construction. Above and below the door opening 2 are arranged slide rods 3 and 4, the said rods being supported in the usual manner, and the main door 5 has bearings 6 at its ends which slide upon the rods.

A stop bar 7 of usual construction is arranged at the side of the door opening for engagement by the door when it is closed, and an auxiliary door 8 is mounted to slide 40 vertically in the main door. The upper part of the main door consists of inner and outer walls spaced apart from each other, as shown more clearly in Fig. 3, and the auxiliary door 8 slides between these walls.

At the lower half of the main door these 45 walls are cut away, in such manner that when the door 8 is lifted to a position near the top of the main door the opening 9 through the main door will be open, permitting access to 50 the interior of the car through the small door. This door has a handle 8^a for convenience in lifting the same, and it is counterbalanced by counterweights 11, which are mounted to slide in guideways 12 in the 55 main door, at the opposite sides thereof, and

at the opposite sides of the space within which the auxiliary door moves.

The counterweights are connected to the auxiliary door by flexible members 13 which, intermediate their ends, pass over pulleys 14 journaled on the uppermost bearings 6. The flexible members are arranged at opposite sides of the top of the door, each being connected to an eye 15 on the door. When the auxiliary door is raised or lowered, 65 the counterweights will balance the same, so that it will be an easy operation to open or close the auxiliary door. The auxiliary door 8 is held in closed position by means of a latch, and the main door is held in closed 70 position by a similar latch.

Each of these latches, one of which is shown in Fig. 7, consists of a hasp 16, which is hinged to a hinge plate 17 on the main door or on the auxiliary door, as the case may 75 be, and each hasp is adapted to engage a staple 18 on the stop plate 7, or on the main door, as the case may be. A hook 19 is provided for engaging each staple, to prevent disengagement of the hasp, each hook being 80 connected to the door by a flexible member 20, a chain in the present instance.

A hood 21 of metal or the like is connected with the top of the main door, the said hood extending over the slide rod 3, and moving 85 in close contact with the side of the car, beneath the eaves, so that rain falling from the eaves will be deflected by the hood from the inferior of the doors.

In use, when the doors are closed, the 90 contents of the car are also inclosed.

I claim:

In combination with a car having a door opening, and a door mounted to slide over and away from over the door opening, said door having an auxiliary door opening at its lower end and extending approximately the full width of the main door and substantially flush with the floor of the car when the door is closed, an auxiliary door for closing the opening, said main door having a passage above the auxiliary door opening in which the auxiliary door is mounted to slide, and having vertical passages at each side of the door opening and of the first named passage, and counterweights in the last named passages and connected to the auxiliary door to operate the same.

ROBERT ANDREW EDGAR.
